UNITED STATES PATENT OFFICE.

JOSEPH E. STAGL, OF BROOKLYN, NEW YORK.

CLOTHES-HANGER.

1,400,633.

Specification of Letters Patent. Patented Dec. 20, 1921.

Application filed April 12, 1920. Serial No. 373,446.

To all whom it may concern:

Be it known that I, JOSEPH E. STAGL, a citizen of the United States, residing at 724 Quincy street, Brooklyn, in the county of 5 Kings and State of New York, have invented a new and useful Clothes-Hanger, of which the following is a specification.

This invention relates to apparatus for extending clothes lines and the like.

10 Some of the objects of the present invention are: to produce an apparatus as characterized which facilitates the hanging of clothes upon a line through a window opening; to include in the apparatus a supporting bracket which may be swung into and out of a room through a window opening for the convenient hanging of the clothes upon a line and their removal therefrom; to provide means at a fixed and convenient position with which to effect the movement of 15 said supporting bracket; to employ an endless rope or line and means for supporting the rope or line so that the same may be moved regardless of the position of the said 20 supporting bracket; to employ means supported by the said bracket for taking up and letting out the rope or the line to allow the said bracket to be swung from one position to another. With these and other objects in view the invention resides in the particular provision, construction and operation of parts hereinafter more fully described and illustrated in the accompanying drawings, in which:

25 Fig. 1 is an elevation of the apparatus of the present invention as it is applied at a window opening—the supporting bracket being shown as extending across the window opening on the outside of a dwelling.

30 Fig. 2 is a horizontal sectional view taken on the line 2—2, Fig. 1.

Fig. 3 is a vertical sectional view taken on the line 3—3, Fig. 1.

Fig. 4 is a detail vertical sectional view 45 taken on the line 4—4, Fig. 1.

Fig. 5 is a detail horizontal sectional view taken on the line 5—5, Fig. 1.

Fig. 6 is a detail horizontal sectional view taken on the line 6—6, Fig. 3.

50 Fig. 7 is a detail view illustrating the block arranged on the rope or clothes line for the attachment of the rope or clothes line in loop form at a point remote from the supporting bracket forming a part of the 55 apparatus.

Referring now more particularly to the

several views of the drawings for all of the details, it will be manifest that, the apparatus of the present invention includes an attaching unit 1 with which the apparatus 60 as a whole is secured fixedly in place at a window opening, and a supporting bracket 2 which is supported for movement by said unit 1 upon a shaft 3 mounted for rotation in bearing lugs 6 and 7. The shaft 3 has 65 a head at the top thereof and a key 4 carried by said shaft is disposed in a key-way or slot 5 in an extension of the bracket 2. It follows that upon movement of the shaft 3 the bracket 2 will be moved accordingly. 70 Movement of the shaft 3 is effected by the employment of a gear 9 attached to the lower end of said shaft, and a worm-gear 10 attached to a shaft 12 mounted for rotation in the part 11 of the unit 1. The shaft 12 has 75 attached thereto a manipulator 13 to turn it. The extension 8 of the bracket 2 receives the shaft 3, and said extension rests on a washer on the part 11 so as to make easy the turning or swinging of said bracket. 80

It is within the present invention to employ a clothes line or the like 29 which is to be supported in a manner so as to be capable of being taken up or let out in the movement of the bracket 2, and allowing 85 the movement of the said line 29 regardless of the position of the bracket 2 which may be brought into a room or which may be moved to a position outside of or without the room. 90

In order to support the line 29 so that the same may be taken up or let out in the movement of the bracket 2, the line is made endless and it carries a block having a pulley 28-8 for the attachment of the line at a point remote from its points of connection with means to be described carried by the bracket 2. A block 23 is arranged for movement on the bracket 2 and the said block has operatively attached thereto pulleys 28-2, 28-4 and 28-6. Pulleys 28-1 and 28-7 are arranged for rotation on a shaft 30 and they are held in spaced relation by a member 31. Looking at Fig. 1 it will be apparent that the line 29 extends from the pulley 28-8 to the pulley 28-1 to the pulley 28-2, thence over the pulley 28-3, thence over the pulley 28-4, thence over the pulley 28-5, thence over the pulley 28-6 to the pulley 28-7 and back over the pulley 28-8. It will be manifest that the 105 pulleys 28-3 and 28-5, and the pulleys 28-1 pulleys 28-3 and 28-5, and the pulleys 28-1 and 28-7 are relatively fixed with respect to 110

each other and with respect to the pulleys 28-2, 28-4 and 28-6. It follows that the rope 29 may be moved about all of the pulleys regardless of the position of the bracket 2.

5 In order that the bracket 2 may be allowed to swing from one position to another there is provided a means A which has connection to the block 23 and serves to allow the line 29 to be taken up as the bracket 2 is swung 10 outwardly to the position shown in Figs. 1 and 2, and to let out the line 29 when the bracket 2 is being swung to a position in which the same will be within a room. The means A includes a rotatable shaft 14 which 15 is carried by the bracket. A gear 15 is attached to the shaft 14 and the said gear meshes with a worm-gear 16 attached to a shaft 18 supported for rotation by plates 17, 17. A manipulator 19 is attached to the 20 shaft 18 and serves for the turning of the shaft 18. A flexible element 20 has one end thereof connected to the block 23, as at 24, and the opposite end thereof is wrapped about the shaft 14. The element 20 passes 25 over pulleys 21 and 22. The pulleys 28-2 and 28-6 move between guides 25, 25 arranged in pairs and forming a part of the bracket 2 to prevent lateral displacement of the block 23. A lug 26 forming a part of 30 the block 23 moves between guides 27 forming a part of the bracket 2 to guide the block 23 in its horizontal movement.

From the foregoing it will be manifest that, upon manipulating the manipulator 13 35 the bracket 2 may be swung into a room so that the portions of the line 29 beyond the bracket may be readily accessible for hanging clothes thereon or for the removal thereof; the bracket may be swung to 40 a position without the room through the window opening so that the lower window sash may be moved to a closed position; the manipulation of the manipulator 19 will allow the block 23 to move in one direction 45 to let out the line 29 as the bracket is moved

into the room, and it will cause the block 23 to move in the opposite direction to take up the line 29 as the bracket is moved out of the room.

What is claimed is:

1. Apparatus including a supported movable bracket, an endless line, means including a movable pulley-block and fixedly arranged pulleys on said bracket for taking up and letting out the said line, a pulley-block on said line adapted to be attached to a fixed support, and means for effecting the movement of said first named pulley-block. 50

2. Apparatus including a movably supported bracket, an endless line, means including a movable pulley-block and fixedly arranged pulleys on said bracket for taking up and letting out the said line, a pulley-block on said line adapted to be attached to a fixed support, and means on said bracket 60 for effecting the movement of said first named pulley-block.

3. Apparatus including a movably supported bracket, an endless rope, means including a movable pulley-block and fixedly arranged pulley on said bracket for taking up and letting out said rope, a pulley-block on said rope adapted to be attached to a fixed support, means for effecting the movement of said bracket and means for moving 70 said first named pulley-block.

4. Apparatus including an attaching unit, a supporting bracket arranged for movement on said unit, means including a movable pulley-block and fixedly arranged 80 pulleys on said bracket for taking up and for letting out an endless flexible element, a pulley-block carried by the flexible element adapted to be attached to a fixed support, means for effecting the movement of the 85 bracket including a manipulating member on the said unit, and means for effecting the movement of the first named pulley-block.

JOSEPH E. STAGL.
